BRAKE HANGER RETAINER

Malcolm S. Johnson, Chicago, Ill., assignor to
Illinois Railway Equipment Company, Chi-
cago, Ill., a corporation of Illinois

Application November 14, 1936, Serial No. 110,842

8 Claims. (Cl. 188—209)

My invention relates to means whereby the brake hangers of railroad cars are pendently supported and retained in place in the sockets formed by the laterally disposed brackets or arms generally formed integral with the truck frame; my improved retainer being more especially adapted for use with the link type of brake hanger at present employed.

The invention has for its object the provision of means which may be easily assembled and readily removed, when occasion requires, and whereby proper brake-shoe key clearance will be provided during brake-shoe replacement, and the hangers or links will be held in proper position.

The invention also contemplates retainer means whereby undue vibratory action between the retainer and the supporting arms or brackets of the truck will be eliminated and a non-chattering relation provided between the socket portion of the arm or bracket of the truck frame and the retainer means.

Another object of my invention is to provide a retainer composed of complementary parts made interchangeable so that any resulting wear between the hanger or link and the supporting member of the retainer means may be taken care of by the interchange or reversal of the retainer means; the different parts of said means being adapted to compensate for variations in the dimensions of the bracket opening.

The foregoing enumerated objects and advantages of my invention, as well as other advantages inherent in the construction, will be more readily comprehended from the detailed description of the accompanying drawing, wherein—

Figure 1 is a side elevation of the supporting arm or bracket of the truck frame, a portion of the truck frame being shown in section, with the lower part of the link or hanger broken away and my improved retainer means secured in place.

Figure 2 is a vertical sectional view taken along the line 2—2 of Figure 1.

Figure 3 is a cross sectional view taken on the line 3—3 of Figure 2 looking in the direction of the arrows.

Figure 4 is a perspective view of the link-engaging side or inner face of one member of the retainer means.

Figure 5 is a perspective view of the socket or outer end portion of the supporting arm of the truck frame.

The retainer consists of a pair of complemen-

tary members 10 identical in construction and adapted to be arranged in superposed relation to provide a suitable channel to receive one end of a hanger 11 therebetween; the superposed members 10 being intended to be inserted into the socket 12 formed in the extension or arm 13 which is generally formed integral with the truck frame a portion of which is shown at A.

The brake beam hanger pocket or socket 12, at the free end of the laterally disposed arm 13, is formed by the vertically spaced portions or walls 14, 15. The longitudinal edge of the portion 14 on its inner surface is provided with a flange or transverse shoulder 16 which tapers or increases in transverse dimensions from one end of portion 14 toward the other. This flange 16, at an intermediate point, is shown provided with an enlargement or boss 17 extending inwardly toward the closed side of the pocket 12. see Figure 5.

The longitudinal edge of the other portion or wall 15 is also provided with a flange or shoulder 18, which also tapers or increases in transverse dimensions like shoulder 16, but the taper is in the opposite direction from the taper of shoulder 16, as shown in Figure 5.

The pocket 12 in the arm 13, in addition to receiving the link or hanger 11, is also intended to receive the link or hanger retaining means consisting of a pair of plates or members 10, 10 which are identical in construction. The construction of these plates is more clearly shown in Figure 4 where the hanger receiving side of the plate is shown with one longitudinal edge of the plate curving toward the hanger receiving side 35 as shown at 19, to constitute one side or wall of the semi-cylindrical groove 20 whose opposite side or wall is formed by the longitudinal rib 21.

The rib 21 at one end of the plate terminates in the laterally disposed ear or lobe 22 provided with a suitable bolt-receiving hole 23. The longitudinal rib 21 is arranged a slight distance removed from the longitudinal edge 24 of the plate and this distance increases toward one end because the transverse width of the plate increases 45 toward the end provided with the lobe or ear 22.

As a result, the member is provided with a tapering or sloping longitudinal edge 24 which corresponds in degree of slope or taper to the taper of the shoulders 16 and 18 in the socket 50 or pocket 12 of the bracket arm 13.

The longitudinal side 24, intermediate of the ends of the plate, is also provided with an indentation or socket 25 of dimensions sufficient to receive the enlargement or boss 17 when the

plate is inserted in the pocket 12; the boss 17 and socket 25 providing an interlocking engagement with the particular member 10 which contacts the walls of socket 12 provided with boss 17.

5 This causes the said member to be held against lengthwise movement during insertion of the other member 10 and allows a binding relation between both members 10 to be effected.

In assembling my improved retainer means, 10 one member 10, with the upper end of the hanger in its groove 20, is first inserted in the pocket or socket 12 of the supporting arm 13; the member 10 being positioned so that the enlargement or boss 17 on the lower wall of pocket 12 is in register with and enters the socket 25 in the longitudinal side 24 of the member 10. This causes an interlocking engagement whereby the proper position of the initially inserted member 10 is determined and sliding movement of the member 20 lengthwise of the pocket prevented. After the lower member 10 with the superposed hanger 11 is in place as described, the second or upper member 10 is then inserted endwisely into the pocket with the narrow portion of the longitudinal side or flange 24 initially entering the pocket. 25

The gradually increasing lateral flanges of the two members cooperating with the oppositely tapering flanges on the upper and lower walls of the pocket or socket, will cause the two superposed members to be forced toward the rear or inner side of the pocket or socket.

30 The superposed relation of the two members 10 and the wedging of said members toward the rear or inner side of the socket is controlled and effected through the action of the nut 26 screwing lengthwise of bolt 27 which latter is inserted through the apertures 23 in the lobes 22 of the superposed members 10, 10.

35 As previously stated, the two members 10, 10 are identical in construction and, therefore, when arranged in the superposed relation, namely with the grooved face 20, of the bottom member disposed upwardly, the lobe 22 of said bottom member will be located at the right as viewed in Figure 1, while the lobe 22 of the upper member 10, when its grooved side 20 is facing downwardly as in Figure 4 will be located at the left as viewed in Figure 1. That is to say, the lobes of the two members will be located at opposite ends of the socket or pocket 12. It is apparent from this arrangement that the screwing up of nuts 26 against one lobe or ear 22 brings the head of bolt 27 against the other lobe or ear and exerts pressure on the superposed plates in opposite longitudinal directions and induces a snug relation between the tapered flanges 24 of the members 10 and the tapered flanges 16 and 18 on the walls of the pocket or socket 12, with the result that vibration and chattering of the retainers are prevented.

40 With both members 10 identical in construction any wear that may take place on the lowermost member 10 (the member which carries the hanger and weight of the brake mechanism) can be taken up by reversing the members with the result that the brake mechanism will always be maintained at the proper elevation required for effective braking operation.

45 With my improved retainer wherein the superposed members, through the action of the tapered flanges, are wedged toward the rear of the socket, compensation for variations in the dimensions of the pocket or socket is afforded and means for holding the superposed members tightly in the brackets is also provided.

With my improved retainer means shown and described, greater clearance for the brake shoe key is provided during brake shoe replacement, because the need for perpendicularly disposed bolts as heretofore employed is eliminated.

5 I have described what I believe to be the best embodiment of the invention, although it may be possible to somewhat modify the particular construction shown without departing from the spirit of the invention as defined by the appended claims.

What I claim is:

1. A brake hanger retainer comprising, in combination with a truck frame provided with vertically spaced laterally disposed lugs, the outer 15 ends of the lugs on their opposing faces being each provided with a tapering flange, the flanges of the lugs tapering in opposite directions; a pair of complementary members arranged in superposed relation between said lugs and each being 20 grooved longitudinally to combinedly provide a hanger receiving socket, the members having oppositely tapering flanges adapted to engage the tapering flanges of said lugs, each member having a laterally disposed apertured lobe; and 25 means adapted to extend through the apertures of the lobes and tend to cause the tapered flanges of the members to move lengthwise of the tapered flanges of said lugs and thereby force the complementary members toward the inner ends 30 of said lugs.

2. A brake hanger retainer comprising, in combination with a truck frame having a horizontally disposed pocket open at one side and both ends, the upper and lower walls of the pocket on their opposing faces being flanged, the flange of the upper wall increasing in horizontal thickness in a direction opposite to the increase in thickness of the flange on the lower wall, one of the flanges being provided with a laterally disposed abutment; a pair of complementary members arranged in superposed relation in said pocket, each member being longitudinally grooved on one face to combinedly provide a hanger-receiving socket, said members having oppositely tapering flanges 40 adapted to engage respectively the tapering flanges on the upper and lower walls of said pocket, said members being socketed to receive said abutment in the pocket to hold the members against lengthwise movement of the pocket, 45 each member being provided at an end with a laterally disposed apertured lobe, the lobes of the two members being arranged in parallel spaced relation with each other; and means adapted to engage both of said lobes to exert pressure on 50 said members in opposite directions and whereby the cooperating tapered flanges of the members and upper and lower walls of the pocket will cause said members to move toward the inner side of the pocket.

55 3. In a brake hanger retainer of the character described, a pair of complementary members each member being grooved lengthwise of its face to receive a brake hanger and each member intermediate of its ends being provided with a lug 60 receiving socket, while one end of each member is provided with a laterally disposed apertured lobe extending substantially at right angles to the direction of the grooves, and means adapted to extend through the apertures in said lobes 65 and to force said members in opposite directions.

4. A brake hanger retainer of the character described, comprising, in combination with a truck frame having a horizontally disposed pocket open at the ends and one side, the upper and 70

lower walls of the pocket on their opposing faces having tapered flanges, the taper of the flange of the upper wall being in a direction opposite to the taper of the flange on the lower wall, one 5 of said walls being provided with a lug; a pair of complementary members adapted to be superposed in said pocket, each member being grooved lengthwise with the groove of the one matching the groove of the other member to combinedly 10 provide a hanger-receiving channel, each member on its outer surface being socketed to register with and to receive the lug in said pocket and thereby hold the member against movement lengthwise of the pocket, said members along one 15 longitudinal side having laterally disposed tapered flanges adapted to coat with the tapered flanges on the upper and the lower walls of said pocket, each member on its flanged side being provided with a laterally disposed apertured lobe; and 20 means adapted to cooperate with the apertured lobes of the two members whereby the cooperating tapered flanges cause said members to move toward the rear side of said pocket.

5. A brake hanger retainer of the character 25 described comprising, in combination with the hanger receiving socket on the truck frame whose walls are provided with tapered surfaces, a pair of complementary members formed to provide a hanger receiving channel when said members 30 are arranged in superposed relation in said socket, said members being provided with surfaces adapted to cooperate with the tapered surfaces on the walls of said socket and thereby effect a binding relation between the members and the 35 walls of said socket, and adjustable means whereby the superposed relation between the members is controlled.

6. A brake hanger retainer of the character 40 described comprising, in combination with a truck frame provided with a hanger receiving socket, a pair of complementary members formed to provide a hanger receiving channel when arranged in superposed relation in said socket, the socket walls and said members having coating surfaces 45 whereby the members are wedged toward the inner side of the socket when the members

are forced longitudinally in opposite directions, and adjustable means operatively associated with both of said members for controlling the superposed relation of said members.

7. A brake hanger retainer comprising, in combination with a truck frame provided with a socket open at the ends and at one side, with the upper and lower walls of the socket having surfaces tapering transversely of the socket, a pair of complementary members adapted to be 10 arranged in said socket and each having a groove disposed lengthwise, the groove of the one member corresponding to the groove of the other member to provide a hanger receiving channel, the members having tapering surfaces adapted 15 to cooperate with the tapering surfaces in the socket of the truck frame, each member at one end being provided with a laterally disposed lobe extending substantially at right angles to the direction of the channel, and means adapted 20 to cooperate with the lobes of both members to exert pressure on said members in opposite directions whereby the tapered surfaces in the socket and of the members cause the latter to be forced toward the inner side of the socket. 25

8. A brake hanger retainer comprising, in combination with a truck frame having a socket open at the ends and at one side with the upper and lower walls of the socket having surfaces tapering transversely of the socket and one wall 30 of the socket provided with a boss, a pair of complementary members adapted to be arranged in superposed relation, the opposing faces of the members being grooved to combinedly provide a hanger receiving channel and having tapering 35 surfaces adapted to cooperate with the tapering surfaces in the socket of the truck frame, the members having flanges disposed beyond one of the longitudinal sides and provided with sockets corresponding with the boss on the wall of 40 the socket, the flanged sides of the members being provided with apertured lobes, and means adapted to extend through the apertures of the lobes of both members to exert pressure on said members in opposite directions. 45
